UNITED STATES PATENT OFFICE

99,078

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application December 2, 1935, Serial No. 59,859

Term of patent 14 years

To whom it may concern:

Be it known that I, John F. Gaul, Jr., a citizen of the United States of America, residing at No.
1110 Van Houten Avenue, in the town of Clifton,
State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The area contained within the dot and dash lines constitutes one design unit, which unit is repeated in the relation indicated over the entire face of the fabric.

I claim:

The ornamental design for a textile fabric or similar article of manufacture substantially as shown and described.

JOHN F. GAUL, JR.
